UNITED STATES PATENT OFFICE.

FRANK L. CAPPS, OF MILFORD, CONNECTICUT, ASSIGNOR TO COLUMBIA PHONOGRAPH COMPANY, INC., OF BRIDGEPORT, CONNECTICUT, A CORPORATION OF NEW YORK.

DESIGN FOR A SUPPORT FOR ELECTRIC PICK-UP.

Application filed September 1, 1927. Serial No. 23,267. Term of patent 7 years.

To all whom it may concern:

Be it known that I, FRANK L. CAPPS, a citizen of the United States, residing at Milford, in the county of New Haven and State of Connecticut, have invented a new, original, and ornamental Design for a Support for Electric Pick-Up, of which the following is a specification, reference being had to the accompanying drawing, forming a part thereof.

Fig. 1 is a plan view of the article showing my new design.

Fig. 2 is a side elevation.

I claim:

The ornamental design for a support for electric pick-up, substantially as shown.

FRANK L. CAPPS.
